(54) **SAW TEETH, CUTTING**

(76) Inventor: **Andrew T. Mervin**

Andrew H. Merrim, Munsey, Pa.
Letters Patent.

The schedule referred to in these Letters Patent and making part of the same, containing a description in the words of the said Andrew H. Merrim, himself of his improvement in the machine for cutting Saw-teeth and Punching.

Be it known that Andrew H. Merrim of the Borough of Munsey, Lycoming Co, State of Pennsylvania have made an improvement in the machine for cutting Saw-teeth, which is described as follows. The bed to receive the different parts of the apparatus for cutting saw-teeth, the stock to receive the dies, the levers used for working the cutters are somewhat similar to those already in use. My improvement consists in having moveable dies, the plate used for securing the female die, the screws & plate for regulating the stock containing the dies, the regulator for determining the size and shape of the teeth. The moveable dies are made of steel or cast iron, they are made in the shape of the tooth required, I have dove-tail shanks for securing them in the stock. A piece of sheet lead is also used for making them firm & steady. The plate for holding down the female die is made of cast iron extending to the front of the female die and is made fast by nut and screw on the top of the bed or frame. The screws & plate for regulating the stock containing the male dies is let in through the side of the bed or frame and press against a moveable plate which presses against the stock containing the male dies and are for the purpose of making the dies out true. There is also a screw working through a bar on the top, passing on the stock and for keeping it steady. The regulator for determining the size and shape is made of a piece of iron having a screw-bolt for turning off, fastened to a spring in the bed made for that purpose.

his

This slot will be made sufficiently long to admit the teeth of a circular saw to be cut in the same manner as those of any other saw. The bed with the whole apparatus can be made fast to a bench or other stand by means of a dog & a hand screw. In operation, the male die of the shape of the teeth required is fastened in the stock and the female die fastened down by the plate screw. The saw plate is set in front of the female die on its edge. The lever which works the stock and male die is then brought down, this forces the male die through the plate of the saw into the female die and the tooth is thus cut - pieces cut out being forced forward - the invention here claimed and desired to be secured by letters Patent consists in the before described moveable die, the plate for holding down the female die, the screws and plate for regulating the stock, the regulator for determining the size & shape of the teeth, with the arrangement and adaptation of the several parts of the machine for cutting & running saws right & left and for purchasing.
